UNITED STATES PATENT OFFICE.

ALONZO HITCHCOCK, OF NEW YORK, N. Y.

IMPROVEMENT IN MODE OF HANGING DOORS.

Specification forming part of Letters Patent No. **41.006**, dated December 22, 1863; antedated December 13, 1863.

To all whom it may concern:

Be it known that I, ALONZO HITCHCOCK, of New York, in the county and State of New York, have invented a new and useful Improvement in Hanging Doors; and I do hereby declare that the following is a full, clear, and exact description of the same, reference being had to the accompanying drawing, making a part of this specification, and to the letters of reference marked thereon.

In sliding doors hitherto the extent of the support has been restricted to the width of the doorway, which is usually so much less than its height that the tendency to cant or tilt and jam diagonally has been productive of great inconvenience.

The object of my invention is to extend the width of the support in such a manner that the application of the force necessary to open or close the door will cause it to move in the required direction without this objectionable diagonal tendency; and it consists in hanging the door on a tube or bar which projects beyond one or both of its edges, and slides or travels on another fixed bar or tube in such a manner that the weight of the door preponderates over the opening or closing face and retains it in its proper vertical position.

To enable others skilled in the arts to which it appertains to make and use my invention, I will proceed to describe its construction and operation with reference to the drawing, which represents the end frame of an ordinary street-railway car with a door hung and applied according to my said invention.

The frame-work *a* is made in the usual manner. The door *b* is hung by the clamps *c* upon the tube *d*, which extends beyond the edge to

which the handle is affixed, and is supported on the rod *e*, that passes through its interior and is secured to the frame by means of screw-nuts at its ends. The rod *e* may also be made tubular for the purpose of combining lightness with stiffness and strength, and it may be supported in the vicinity of the middle of its length by the suspension-rod *f*, which passes through a slot in the upper part of the tube *d* between the clamps. The door should be made somewhat wider than the opening of the doorway, so that when it is entirely closed the rear edge is retained within the casing, to prevent swinging.

Having thus described the manner in which I prefer to apply my invention, I would here state that it may be modified and arranged in a variety of ways without departing from its nature as herein set forth. The door, instead of being suspended at its upper end, may be supported at the bottom on a base similarly extended, or it may be hung at both the bottom and the top, and it may travel on rollers or wheels, instead of merely sliding on plane surfaces. In double doors the points of support may be placed slightly out of center, so that the sliding tubes or bases may pass and lap each other when the doors are closed.

I claim as my invention and desire to secure by Letters Patent—

1. Hanging a sliding door on an extended support, substantially in the manner described.
2. Suspending a door on a tube, whether the same is extended or not.

A. HITCHCOCK.
